UNITED STATES PATENT OFFICE.

EDWARD HAYES, OF ROCHESTER, NEW YORK.

GENERATOR.

SPECIFICATION forming part of Letters Patent No. 571,762, dated November 24, 1896.

Application filed April 1, 1895. Serial No. 543,942. (No model.)

To all whom it may concern:

Be it known that I, EDWARD HAYES, of Rochester, in the county of Monroe, in the State of New York, have invented new and useful Improvements in Generators, of which the following, taken in connection with the accompanying drawings, is a full, clear, and exact description.

My invention relates to improvements in generators of the class set forth in my previous patent, No. 480,002, dated January 3, 1893, and has for its object the production of a device which is particularly simple in construction and practical in operation; and to this end it consists, essentially, in the construction and arrangement of the component parts of the generator, all as hereinafter more particularly described, and pointed out in the claims.

In describing this invention reference is had to the accompanying drawings, forming a part of this specification, in which like letters indicate corresponding parts in all the views.

Figure 1 is a vertical section of my improved generator. Fig. 2 is an elevation of a portion of the water-containing drum and adjacent upright heads connected thereto. Fig. 3 is an elevation of the connection between the water-containing drum and one of the upright heads of the generator. Fig. 4 is a vertical section, taken on line 4-4, Fig. 3. Figs. 5 and 6 are respectively elevation and inverted plan of one of the detached nipples or pipes of the connection seen at Figs. 3 and 4. Figs. 7 and 8 are respectively elevation and top plan of the other nipple or pipe of said connection, and Fig. 9 is a top plan of the detached coupling of said connection.

A represents the outer shell of my improved generator, which is of any desirable form, size, and construction, and is here shown as composed of brick, although it may be otherwise formed if desired. This shell preferably consists of top and upright walls a a' , which may be provided with suitable ash, fuel, and cleaning doors, not necessary to herein illustrate and describe. A suitable intermediate wall a^2 is interposed between opposite upright walls a' of the shell A, and the top face or edge of the wall a^2 is consid-

erably separated from the adjacent face of the top wall a . A combustion-chamber a^3 and a fire-passage a^4 are arranged on opposite sides of the wall a^2 , and the upright wall a' adjacent to the fire-passage is provided with an outlet a^6 , which is arranged in substantially the same horizontal plane as the base of the combustion-chamber and opens 55 into a smoke-pipe a^7 . If desired, the wall a' adjacent to the pipe a^7 may be provided with an upper outlet a^8 , which may receive a lateral branch a^9 from the pipe a^7 .

B is a water-containing drum of any desirable construction, arranged at the outer side of the wall a^2 at one side of the combustion-chamber a^3 and in proximity to the adjacent upright wall a' and the horizontal plane of the outlet a^6 . A pipe B' is connected 65 to the drum B for discharging the return or feed water of the generator thereinto in order that the escaping products of combustion may be deprived of their heat to a maximum degree, but it is obvious that the return or 70 feed water may be admitted by any other suitable part of the generator.

b are upright heads of any desirable construction mounted above the drum B and suitably connected thereto. The connection for 75 each of the heads b preferably consists of nipples or pipes c c' , having their adjacent ends suitably interlocked, and a coupling c^2 engaged with said ends. As here illustrated, the end of the nipple or pipe c , engaged by 80 the coupling c^2 , is provided with annular and longitudinal shoulders c^3 c^4 , projecting from its end edge and an annular screw-threaded surface c^5 , increasing in diameter from said edge. The adjacent end of the nipple or pipe 85 c' is formed with annular and longitudinal sockets c^6 c^7 in its end edge for receiving the shoulders c^3 c^4 , and is provided with an annular screw-threaded surface c^8 , decreasing in 90 diameter from said edge. The adjacent ends 95 of the surfaces c^5 c^8 are of substantially the same diameter and are normally arranged in close proximity, as clearly seen at Fig. 4. The taper of said surfaces c^5 c^8 is substantially 100 uniform in order that both may be readily engaged by the coupling c^2 , which is formed with a tapering conical inner periphery c^9 , provided with screw-threads meshing with the threads of the surfaces c^5 c^8 . As the coup-

ling c^2 is screwed toward the end of the surface c^5 of greater diameter, independent revoluble movement of either of the nipples or pipes c^4 is prevented by the shoulder c^4 and said coupling is secured to the adjacent ends of the nipples or pipes c^4 with a particularly tight joint. The described construction of connection for securing the heads c to the drum B is particularly applicable for said purpose, but it is obvious that any other suitable connection may be used, if desired.

D are suitable heating-coils projecting laterally from the heads b above the fire-passage a^4 , the intermediate wall a^2 , and the combustion-chamber a^3 , and having their outer or free ends arranged in proximity to the adjacent upright wall of the case A, which forms one of the side walls of the combustion-chamber. The coils D are usually substantially U -shaped and are preferably arranged one within the other with their opposite branches inclined from each other from their outer ends toward the upright heads b , as the circulation therethrough is greatly facilitated by such arrangement and inclination.

As here illustrated, the coils D are composed of pipes connected together; but bent tubes may be used, if desired. The described construction of coils is particularly applicable for use with this generator, but it will be understood that my invention is not limited thereto.

The products of combustion impinge against the free ends of the coils D and then pass over the intermediate wall a^2 and through the fire-passage a^4 to the outlet a^6 and the pipe a^7 . In order that the products of combustion may be compelled to rise somewhat above the wall a^2 , I preferably support a plate d above the top face of the wall a^2 and extend the same between the heating-coils projecting from adjacent upright heads b . If desired, this plate may be supported by the wall a^2 , as illustrated, or it may be suitably engaged with the adjacent heating-coils and it may consist either of a single piece extending lengthwise of the wall a^2 and formed with perforations for the heating-coils D or a number of comparatively narrow strips arranged between adjacent series of heating-coils.

E is a steam or hot-water drum arranged beneath the top wall a in proximity to the upright wall a' arranged opposite to the wall a^2 and forming the side wall of the combustion-chamber a^3 .

The drum E is connected to the upper ends of the head b by suitable steam or hot-water passages, as pipes e , arranged substantially parallel with the top wall a and having downturned ends e' , secured by connections of suitable construction. The connections preferably consist of nipples or pipes e^2 e^3 and couplings e^4 of substantially the same construction as the corresponding parts c c' c^2 , previously described. The steam or hot water may be withdrawn from the drum E by an outlet-pipe E' of any desirable construc-

tion. A generator of the described construction is particularly applicable for use in generating steam, but it is equally suitable for hot-water heating, and in that event the heated water is discharged through the pipe E' and may be returned through the pipe B' .

The operation of my generator will be readily understood upon reference to the foregoing description and the accompanying drawings, and it will be particularly noted that its heating-coils are free to expand and contract and convey the circulating water in short paths directly above the heated products of combustion, that the steam or hot water is withdrawn from a drum arranged in its top and connected independently to a series of upright heads provided with the heating-coils, and that the products of combustion emerge from the generator at substantially the same point that the return water enters the same.

The exact detail construction and arrangement of the parts of my generator may be somewhat varied without departing from the spirit of my invention, and hence I do not herein specifically limit myself thereto.

Having thus fully described my invention, what I claim as new, and desire to secure by Letters Patent, is—

1. In a generator, the combination of a combustion-chamber, a horizontal water-containing drum arranged at one side of the combustion-chamber, upright heads mounted above the horizontal drum and connected thereto, and substantially U -shaped heating-coils projecting laterally from the upright heads and having their opposite branches inclined from each other from their outer ends toward the upright heads, said coils being arranged with their outer ends above the combustion-chamber and their opposite ends at one side thereof, substantially as and for the purpose specified.

2. In a generator, the combination of an outer shell having top and upright walls, a combustion-chamber arranged in proximity to one upright wall, a water-containing drum supported in proximity to the opposite upright wall, upright heads mounted above the water-containing drum and connected thereto, heating-coils projecting laterally from the heads and arranged with their outer ends above the combustion-chamber in proximity to the adjacent upright wall and their opposite ends at one side of the combustion-chamber, substantially as and for the purpose set forth.

3. In a generator, the combination of an outer shell having top and upright walls, a combustion-chamber arranged in proximity to one upright wall, a water-containing drum supported in proximity to the opposite upright wall, upright heads mounted above the water-containing drum and connected thereto, heating-coils projecting laterally from the heads and arranged with their outer ends above the combustion-chamber in proximity

to the adjacent upright wall and their opposite ends at one side of the combustion-chamber, a drum arranged in proximity to the top wall and the upright wall adjacent to the combustion-chamber, and connections between the heads and the latter drum arranged adjacent to the top wall, substantially as and for the purpose described.

4. In a generator, the combination of an outer shell having top and upright walls, one of the upright walls having an outlet for the products of combustion, a combustion-chamber arranged adjacent to the opposite upright wall, a wall interposed between said upright walls and formed of less height than the same, a fire-passage between the outlet and the combustion-chamber, upright heads adjacent to the wall provided with the outlet, and heating-coils projecting from the heads above the fire-passage, the intermediate wall and the combustion-chamber, substantially as and for the purpose set forth.

5. In a generator, the combination of an outer shell having top and upright walls, one of the upright walls having an outlet for the products of combustion, a combustion-chamber arranged adjacent to the opposite upright wall, a wall interposed between said upright walls and formed of less height than the same, a horizontal water-containing drum arranged adjacent to the outlet, upright heads mounted above the horizontal drum and connected thereto, and heating-coils projecting laterally from the upright heads above the intermediate wall and the combustion-chamber, substantially as and for the purpose specified.

6. In a generator, the combination of an outer shell having top and upright walls, one of the upright walls having an outlet for the products of combustion, a combustion-chamber arranged adjacent to the opposite upright walls with its base in substantially the same

horizontal plane as the outlet, a wall interposed between said upright walls and formed of less height than the same, a horizontal water-containing drum arranged adjacent to the outlet, upright heads mounted above the horizontal drum and connected thereto, heating-coils projecting laterally from the upright heads above the intermediate wall and the combustion-chamber, a drum arranged in proximity to the top wall and the upright wall adjacent to the combustion-chamber, and connections between the heads and the steam-drum arranged adjacent to the top wall, substantially as and for the purpose specified.

7. In a generator, the combination of a combustion-chamber, a horizontal water-containing drum arranged at one side of the combustion-chamber, upright heads mounted above the drum, nipples or pipes projecting from said drum and heads and having their adjacent ends interlocked and provided with annular screw-threaded surfaces, one of said surfaces decreasing gradually in diameter from its outer end, and the other surface having its outer end of substantially the same diameter as the adjacent end of the former surface and increasing gradually in diameter toward its opposite end, and a coupling having a tapered screw-threaded inner periphery engaged with said annular surfaces, substantially as and for the purpose described.

In testimony whereof I have hereunto signed my name, in the presence of two attesting witnesses, at Rochester, in the county of Monroe, in the State of New York, this 10th day of May, 1894.

EDWARD HAYES.
